(57) **CLAIM**

The ornamental design for a computer casing, as shown and described.

DESCRIPTION

FIG. 1 is a front perspective view of a computer casing showing a first embodiment of our new design;

FIG. 2 is a front side view of the computer casing of FIG. 1;

FIG. 3 is a rear side view of the computer casing of FIG. 1; FIG. 4 is a top side view of the computer casing of FIG. 1; FIG. 5 is a bottom side view of the computer casing of FIG. 1;

FIG. 6 is a right side view of the computer casing of FIG. 1; FIG. 7 is a left side view of the computer casing of FIG. 1; FIG. 8 is a perspective view of a computer casing showing a second embodiment of our new design;

FIG. 9 is a front side view of the computer casing of FIG. 8;

FIG. 10 is a rear side view of the computer casing of FIG. 8;

FIG. 11 is a top side view of the computer casing of FIG. 8;

FIG. 12 is a bottom side view of the computer casing of FIG. 8;

FIG. 13 is a right side view of the computer casing of FIG. 8; and,

FIG. 14 is a left side view of the computer casing of FIG. 8.

The broken lines showing portions of the computer casing form no part of the claimed design.

1 Claim, 14 Drawing Sheets
